HAIR DRIER ATTACHMENT

Hazel Collins, Long Beach, Calif.

Application July 29, 1957, Serial No. 674,778

9 Claims. (Cl. 34—90)

The present invention relates to an attachment for a hair drier of the large permanent type, the attachment being particularly adapted for use in a cosmetological establishment for drying large numbers of combs and brushes.

Many conveniences are now available in a modern cosmetological establishment, however, the continuing demand for higher standards of work requires still further improvements to be made. For example, typical state laws establish very strict standards for cleanliness and sanitation, which with existing types of apparatus imposes a substantial expense upon the owner of the cosmetological establishment.

The average beautician during the course of his or her working day uses a large number of combs and brushes, each of which must be thoroughly cleaned prior to any re-use thereof. For example, one operator might use a dozen brushes and forty combs in a single day. Also, other apparatus such as hair nets and clips which are used on a patron's head must be sterilized before each use.

Cleaning procedure which is made mandatory by a typical state statute involves a number of separate steps, one of which is the drying of the combs, brushes and other apparatus. Equipment heretofore available for this particular purpose has been either inadequate or exorbitantly expensive, hence the attachment provided by the present invention.

Cleaning procedure established by a typical state statute for the cleaning of beauticians' combs and brushes includes the following separate steps:

- (1) Scrubbing the combs and brushes with soap and water.
- (2) Immersing the combs and brushes for at least twenty minutes in a wet sterilizing agent, such as chlorosol or formalin.
- (3) Rinsing the combs and brushes with clean water.
- (4) Drying the combs and brushes.
- (5) After drying, retaining the combs and brushes in a dry sterilizer until their next use.

The step with which the present invention is involved is the particular step of drying the combs and brushes, being only one phase of the over-all cleaning and sterilizing process.

Conventional apparatus such as a drier of the infra-red type may be obtained for drying combs and brushes, however, this is rather an expensive item of equipment for even a large cosmetological establishment and also requires valuable space. It is possible to use a conventional hair drier of the large permanent type for the purpose of drying combs and brushes, and this is the most generally accepted method, but it has many inconveniences and shortcomings. Combs and brushes may be inserted within the forward cavity of the drier head of a hair drier but the capacity is quite limited. Furthermore, much difficulty is encountered with having the combs and brushes fall out of the drier onto the floor and thus requiring complete re-sterilization; or where

2

an upholstered chair is associated with the hair drier as part of a unitary installation the difficulty is that excess moisture runs out onto the chair and ruins the upholstery, or the wet combs and brushes fall out of the hair drier onto the chair with the same result.

An object of the present invention, therefore, is to provide an inexpensive attachment which may be used in conjunction with a conventional hair drier of the large permanent type for drying large numbers of combs and brushes in a cosmetological establishment.

Another object of the invention is to provide such an attachment which is small and inexpensive and may be conveniently used or stored away while not in use.

A further object of the invention is to provide such an attachment in which a large quantity of combs and brushes may be conveniently carried from the place where they have been rinsed during the cleaning process, which may be attached to the hair drier for drying the combs and brushes, and which may then be conveniently detached from the hair drier for carrying the combs and brushes to the dry sterilizer.

Still another object of the invention is to provide a drier attachment for use in drying combs and brushes, as part of the over-all process of cleaning and sterilizing the combs and brushes, and which may be easily kept at least as clean and sanitary as the equipment used in other steps of the cleaning and sterilizing process.

Yet a further object of the invention is to provide a drier attachment for drying large quantities of combs and brushes, and comprising a heavy fabric bag having an end opening, a top opening, and a flexible metal band encircling the end opening and adapted for being removably inserted into the drier head of a hair drier of the large and permanent type.

The above and other objects and advantages of my invention will be more readily understood from the following description in conjunction with the accompanying drawing, in which:

Figure 1 is a perspective view of the presently preferred form of my novel drier attachment, showing the manner of its attachment to a conventional hair drier of the large and permanent type;

Figure 2 is a vertical cross section view of Figure 1 and shows the manner in which a large quantity of combs and brushes are held in my novel drier attachment;

Figure 3 is a perspective view of the novel drier attachment;

Figure 4 is a layout drawing showing the shape of the main fabric piece used in the drier attachment of Figure 3; and

Figure 5 is a detail view of the adjustment mechanism for the flexible metal band used in the drier attachment of Figure 3.

Referring now to the drawing, and particularly to Figures 1 and 2 thereof, a conventional hair drier Z has attached thereto a novel drier attachment A, the latter representing my invention. Drier Z includes a substantially cylindrical drier head 10 having an open end 20 and a closed end 25, closed end 25 having a plurality of air ports 11 therein by means of which air may be admitted to the interior of the drier head. A vertical support post 12 provides means for rotatably supporting drier head 10, the support post being attached to the under surface of the drier head. It will be understood that the conventional drier may include means for rotating the drier head so that open end 20 thereof may occupy a substantially vertical plane, as shown in Figures 1 and 2, or may be pointed downwardly to occupy a substantially horizontal plane, or may assume any position intermediate thereto. The conventional hair drier may also be provided with means, not shown, for controlling the

position of the drier head and for fastening or locking the drier head in any selected position.

The drier attachment A includes an elongate fabric bag, one end of which is closed by means of an end piece D and the other end of which is inserted within the drier head. That end of the bag which is inserted within the drier head has an opening H, as is more clearly shown in Figure 3, the opening H permitting warm air supplied by the hair drier to flow into the attachment A. Attachment A also has on its normally upwardly disposed side an access opening G which may be used for inserting combs and brushes into the attachment, or removing them therefrom, and which further provides means for the escape of air forcibly circulated from the hair drier into the attachment.

Within the drier head 10 and adjacent to the closed end 25 thereof there is a circular heating element 13 which is disposed symmetrically about the longitudinal axis of the drier head. A circular shield 14 is disposed adjacent the heating element and shields the inner surface thereof, as well as the surface facing toward open end 20 of the drier head, and precludes burning the head of a person whose hair is being dried within the drier head while at the same time causing heat from element 13 to be reflected toward the rearward or closed portion of the drier head. A fan 17 driven by a motor 18 is symmetrically disposed behind heating element 13 in such a position as to draw unheated air into the drier head through air ports 11 and force the air past heating element 13 and hence out through the open end of the drier head. A number of circular baffles 15 are concentrically disposed about shield 14 and, together with a rigid support structure, are rigidly fastened to the interior surface of drier head 10. A grill 16 covers the area within shield 14 and immediately in front of fan 17.

At the open end 20 of drier head 10 the inner portion of the drier head may be designated as forward cavity 21, being the portion of the drier head which is normally placed over and around the head of a person whose hair is being dried. At the forward edge of drier head 10 is an inwardly extending flange 22 which encircles the entire circumference of the drier head and partially closes off the forward cavity 21. Electrical control switches designated generally as 23 are mounted on the upper exterior surface of drier head 10 and adjacent to flange 22.

Thus it is seen in Figures 1 and 2 that the end of drier attachment A which is inserted into forward cavity 21 of drier head 10 of the hair drier Z is retained therein primarily by the flange 22. A large quantity of combs and brushes J are placed within attachment A and may to some extent rest upon a bottom portion of the fabric bag which extends within forward cavity 21, but predominantly occupy a portion of the fabric bag which is exterior to drier head 10, as is shown in Figure 2.

Reference is now made to Figures 3 to 5 of the drawings illustrating in greater detail the presently preferred form of my invention.

As shown in Figure 3 drier attachment A includes a fabric bag B, a flexible metal band E, and band adjustment clips 41, 42. Fabric bag B includes a main fabric piece C, shown in expanded form in Figure 4, and a circular end fabric piece D.

Fabric bag B is in the shape of a truncated cone having the large end thereof entirely open, the small end entirely closed, and an approximately V-shaped opening in its top surface, the wide portion of this opening being at the large end of the cone. Flexible band E associated with the large end of the cone bridges the wide portion of the V-shaped opening and is adjustable in length so that the effective diameter of the large end of the cone may be either increased or decreased with respect to its normal value. In the preferred form of the invention as shown the top opening is not truly V-shaped but is wider in the middle in order to permit easier access for insert-

ing or removing combs and brushes, and also to permit free flow of heated air generated by the hair drier.

Reference is now made to Figure 4 illustrating how main fabric piece C is cut. A pie-shaped piece of material representing an angular segment of a circle is cut along an inner arc 31. It also has an outer arc 33 corresponding to a radius which is over twice the radius represented by inner arc 31. Straight edges 34, 35 (shown partly in solid and partly in dotted line) interconnect arcs 31 and 33 to define the remainder of the pie-shaped section. Cut outs 36, 37 are then made on the central portions of edges 34 and 35, respectively. An outer fold line 32 which is spaced a short distance from outer arc 33 and concentrically therewith indicates where the fabric is to be folded to provide an open hem within which flexible band E may be inserted.

Figure 5 illustrates flexible band E having its two ends overlapping each other and engaged by a pair of spaced apart clips 41, 42 to provide for adjustment of the band circumference in a well-known manner.

Referring again to Figure 3, the sides of main fabric piece C are hemmed to prevent fraying, and inner arc 31 is sewed to the perimeter of fabric piece D, all in a conventional manner. Band E has its two ends projecting outwardly from the respective ends of the open hem which is defined by fold line 32, and are fastened together in the manner shown in greater detail in Figure 5.

The manner of use of my invention is very simple. A quantity of combs and brushes which have been rinsed are placed in the fabric bag which is then transported to an available hair drier which has its drier head clamped in a horizontally aligned position. Flexible band E of the drier attachment is folded inwardly upon itself to decrease the effective radius of the large end of the bag and is inserted within the drier head before being released so as to resume its normal shape. The attachment is then retained in position due to friction between the bag and the inner surface of the drier head, and primarily because flange 22 makes the diameter of the open end of the drier head smaller than the diameter of flexible band E.

Many different types of hair dryers are commercially available at the present time and all of them utilize a drier head substantially as shown and having a forward cavity therein as well as an inwardly extending flange similar to flange 22. The diameter of the drier head and of the flange varies from one type of hair drier to the next, however. Thus the adjustable length of flexible band E may be varied by at least four inches so that it will work reliably with any one of the standard types of hair dryers.

After the combs and brushes have been dried, the drier attachment may be removed from the hair drier simply by grasping flexible band E and folding it inwardly upon itself, in the same manner as when the drier attachment was inserted. The entire attachment may then be transported to the dry sterilizer. The need for the beautician to handle the combs and brushes individually during the cleaning and sterilizing process is therefore minimized, and much time is saved in the drying operation.

While flexible band E is preferably made of spring steel having a rust-proof coating, it may be made of any other suitable material. Bag B is preferably made of canvas duck material which is not waterproofed and preferably being No. 10 weight. This material soaks up the excess water from the wet combs and brushes but at the same time the water does not leak out or drip. During the drying operation, the forced draft of warm air generated by the hair drier is forced directly against all of the interior surface of the bag. The reason for this is that the bag has a substantially conical shape as mentioned above. The forced draft against the inner surface of the bag causes moisture to evaporate rapidly and escape through the upwardly disposed access opening G, and also to evaporate rapidly from the exterior sur-

face of bag B. Actual experience has shown that a large quantity of combs and brushes may be dried by using my invention in less time than would be required to dry two or three by the conventional method. The conventional method referred to is that of inserting the wet combs and brushes within forward cavity 21 of the drier head and resting upon the lower inside surface thereof adjacent flange 22.

Another advantage of my invention is that where bag B is made of fabric it may be conveniently washed from time to time in a conventional washing machine, as the need arises. It is therefore easy to keep my novel drier attachment at least as clean as any other apparatus which is used in the process of cleaning and sterilizing the combs and brushes.

While the drawing specifically illustrates only the presently preferred form of my invention, many other forms and variations thereof may be utilized within the scope and spirit of my invention, as well as within the scope of the appended claims. Some of the possible variations will be discussed in the ensuing paragraphs.

Bag B need not be made of canvas but may be made of any suitable fabric. Furthermore, a plastic material may be used, in which case excess moisture from the combs and brushes may be absorbed by placing a dry sterilized towel in the bottom of the bag B and then placing the combs and brushes thereon. Such towel may then be laundered after each use of the drier attachment in order to maintain sanitation.

An entirely different concept for bag B is to employ a type of material which is inexpensive and can be disposed of after a relatively small number of uses. For example, an inexpensive type of heavy paper material would be very suitable. The shape of the bag could then be adapted as necessary in order to achieve maximum economy of manufacture, and it would probably be desirable to fabricate the bag as a single piece of paper.

The shape of bag B need not be restricted to a truncated cone, as shown, nor does the upper opening need to be a modified V, as shown. The principal considerations in determining the shape of the bag are cost of manufacture, effectiveness of the bag in supporting a large quantity of combs and brushes therein, ease of access for inserting or removing combs and brushes, and the effectiveness of the bag in circulating warm air and in drying the combs and brushes. It will in general be preferable to fabricate the bag from a single piece of material.

The support member need not be in the form shown, as a suitable piece of piano wire may be used instead of a flat band. Also, in lieu of flexible band E, it may be convenient to use a band which is co-extensive with the perimeter of the bag opening, together with an adjustable mechanical device for controlling the expansion of the band in order to engage the interior surface of the drier head.

Although my invention is fully capable of achieving the results and providing the advantages hereinbefore mentioned, it is to be understood that it is merely the presently preferred embodiment thereof, and that I do not mean to be limited to the details of construction above described other than as defined in the appended claims.

I claim:

1. In combination with an electric hair drier of the type including a substantially bucket-shaped drier head having an inwardly extending flange encircling the open end thereof, and means positioned within said drier head adjacent the closed end thereof and electrically operable for propelling a current of heated air toward said open end, a comb and brush drying attachment comprising: a container made of a pliable sheet material and having two openings therein which are contiguous and are disposed at substantially a right angle to each other, one of said openings being adapted to be joined to the open end of said drier head, the other of said openings being normally

upwardly disposed; a normally circular spring steel support member encircling said one opening of said container and defining a boundary between said one opening and said other opening; means maintaining said support member in supporting engagement with said container; and means for adjusting the circumference of said support member to be greater than the inner circumference of said flange but less than the inner circumference of said drier head whereby said support member when flexed and inserted within said drier head is operable to support said drying attachment so that heated air generated by said electric drier enters said container via said one opening and leaves via said other opening.

2. In combination with an electric hair drier of the type including a substantially bucket-shaped drier head having an inwardly extending flange encircling the open end thereof, and means positioned within said drier head adjacent the closed end thereof and electrically operable for propelling a current of heated air toward said open end, a comb and brush drying attachment comprising: a container made of a pliable sheet material and having two openings therein which are contiguous and are disposed at substantially a right angle to each other, one of said openings being adapted to be joined to the open end of said drier head, the other of said openings being normally upwardly disposed; a support member encircling said one opening of said container and defining a boundary between said one opening and said other opening; means maintaining said support member in supporting engagement with said container; and means operable after said support member is inserted within said drier head for outwardly expanding said support member so as to be retained against the inner face of said flange, thereby to support said drying attachment.

3. A drier attachment suitable for drying a beautician's combs and brushes and adapted to be removably attached to an electric hair drier, said attachment comprising: a container made of a pliable sheet material and having two openings therein which are contiguous and are disposed at substantially a right angle to each other, one of said openings being adapted to be joined to the open end of the electric hair drier; a normally circular spring steel support member encircling said one opening of said container and defining a boundary between said one opening and said other opening; means maintaining said support member in supporting engagement with said container; and means for adjusting the circumference of said support member to fit within the drier head of the electrical hair drier in relatively tight engagement with the inner surface thereof so that heated air generated by the electric drier enters said container via said one opening and leaves said container via said other opening.

4. A drier attachment as claimed in claim 3 wherein said container has the shape of a truncated cone, said one opening being the base of the cone and said other opening being substantially V-shaped with the wide part thereof being contiguous to said one opening.

5. A drier attachment as claimed in claim 4 wherein said container includes a first circular section forming the vertex thereof, and a second section having an inner arc at a first fixed radius from a predetermined reference point, an outer arc having a second fixed radius with respect to the same reference point and which is at least twice as great as said first fixed radius, the inner arc of said second section being fastened along the circumference of said first section, and the outer arc of said second section being folded over to provide an open hem within which said support member may be inserted.

6. A drier attachment as claimed in claim 3 wherein said pliable sheet material is relatively rigid canvas fabric having a substantial moisture-absorbing capacity.

7. A drier attachment as claimed in claim 3 wherein said pliable sheet material is paper and may economically be disposed of after a very few uses.

8. A drier attachment as claimed in claim 5 wherein said spring steel support member is an elongate flat strip which is normally bent into a circular configuration so that its two ends are overlapping, and in which the means for adjusting the circumference of said support member includes a pair of removable clips holding the two ends of said support member together in frictional engagement.

9. A drier attachment suitable for drying a beautician's combs and brushes and adapted to be removably attached to an electric hair drier of the type which includes an open drier head having an inwardly extending flange encircling the open end thereof, said attachment comprising: a container made of a pliable sheet material and having two openings therein which are contiguous and which are disposed at substantially a right angle to each other, one of said openings being adapted to be joined

5 to the open end of the drier head; a support member enclosing said one opening of said container and defining a boundary between said one opening and said other opening; means maintaining said support member in supporting engagement with said container; and means operable after said support member is inserted within the drier head for outwardly expanding said support member against the inner face of said flange, thereby to support the drier attachment.
